WATER CONTROL FOR BOILERS

John E. Briggs, Detroit, Mich.

Application February 6, 1935, Serial No. 5,268

16 Claims. (Cl. 122—448)

This invention relates to liquid level control devices and more particularly to automatic electric control mechanism for regulating the operation of boilers, tanks, and other fluid receptacles.

5 An important feature of this invention is that the two important incidences of boiler operation, the replenishing with water and the production of heat, are both controlled automatically by an improved electric controller, an important advantage of which is the increased efficiency and 10 safety with which the boiler operates.

An object of this invention is to provide an improved electric controller which is adapted to permit the water level in the tank or boiler to fluctuate in a normal operating range without calling 15 the electrical controller into operation, but when the water level fluctuates to extremes the electric controller is called into operation to restore the boiler to its normal operating range.

20 Another object of this invention is to provide a compact, inexpensively designed, electric controller for boilers, tanks, et cetera, which is adaptable for all types of such devices, whether they are small conventional house boilers or very large 25 steam boilers. A novel relay switch mechanism is employed to accomplish this object and includes a single movable member adaptable in its movement to close various circuits controlling the operation of the boiler. Because of its relatively 30 few parts, this switch is adapted to be designed as a small, unitary structure which can be inconspicuously installed adjacent the boiler.

Various other objects and advantages of my 35 invention will more fully appear from the following specification, appended claims, and accompanying drawings, wherein:

Figure 1 is a diagrammatic illustration of my 40 electric controller and the associated parts of a boiler which it controls, and

Figure 2 is a modification of the device illustrated in Figure 1.

In the embodiments of the invention illustrated in both Figs. 1 and 2 numeral 10 indicates a 45 boiler furnace such as may be employed to heat a house or small building. The boiler portion of the furnace is indicated at 12 and a feed pipe 14 is adapted to supply water to the boiler. The heat producing apparatus is indicated generally at 16 and may comprise a conventional fuel 50 burner to which fuel is delivered by the pipe 18. A blower 20 may be employed if necessary to create a draft of air for the burner. The type of fuel burner is not limited to that disclosed in 55 the drawings, but may be any type such as a fluid

or powdered fuel burner, or it may be a heating apparatus provided with an automatic stoker.

Referring more particularly to Fig. 1, a chamber 22 of the water level gauge type is secured to the boiler and provided with two communications 5 24 and 24' with the boiler so that the water level in the chamber is the same as that in the boiler. Positioned within this chamber are two electric contact members or electrodes, the shorter of the two being indicated at 26 while the longer is designated as 28. These electrodes are insulatively mounted within the chamber at their terminal 10 plugs 30 so that the only electrical relationship that the electrodes have with the furnace is through the water and then only when the water is in contact with the electrodes.

Both the water feed pipe 14 and the fuel delivery pipe 18 are provided with electrically operated valve devices 32 and 34 respectively. These devices may be of similar construction. Valve 20 device 32 is provided with an electromagnetic coil 36 adaptable to influence the valve member 38 to open position. Likewise valve device 34 is provided with an electromagnetic coil 40 adapted to affect the valve member 42 to open position. 25 A main line circuit, which may possess the conventional house voltage, is indicated at 44 and the circuits to the coils 36 and 40 are placed across this line to receive current therefrom. The circuit for coil 36 is indicated at 46. The 30 circuit for coil 40 is indicated at 48.

An automatic relay controller for controlling these circuits is indicated generally at 50. The 35 relay control consists of a coil 52 and an armature 54 provided with switch contacts operable to close and open circuits in a manner to be hereinafter described. The coil 52 derives its power from the secondary of a transformer 56 placed in the main line. The relay coil circuit 58 connects directly with the shorter electrode 26 in 40 the water level chamber.

Both the valve circuits 46 and 48 are open at 45 60 and 62 respectively. They are adapted to be closed by insulated bridging elements 64 carried by the armature 54. In the position of the controller assumed in Fig. 1 the valve circuit 46 is closed at 60 by its respective bridging element 64 while the valve circuit 48, positioned on the opposite side of the movable armature, is open at 62.

The longer electrode 28 is provided with a circuit 66 extending to the relay controller and is adapted to be connected into the relay circuit 58 when the armature has been raised to its upper 55 position. In this position a bridging element 64

will connect the circuit of the longer electrode into the relay circuit so that the relay coil 52 will now have branch circuit 58 and branch circuit 66 in communication with the water in the boiler. This second branch circuit, the electrode 28 and its lead 66, forms a retention circuit for the relay coil retaining the latter in energized condition even after the means which has caused the energization of the coil has been rendered 10 inoperative. This operation will be described in more detail hereinafter.

To describe the operation of the automatic controller illustrated in Fig. 1 it is assumed that the water level in the boiler is below the end of the 15 longer electrode 28. The main line switch A is closed and due to the closure of the coil circuit at 60, valve member 38 is withdrawn to open position permitting feeding of water through conduit 14 to the boiler. The water level rises 20 within the boiler and its contact with the longer electrode 28 produces no effect for the latter is in open circuit position at the relay controller. The water continues to rise until it approaches the shorter electrode 26, and during this interim the 25 valve device 34 is cutting off the flow of fuel to the heat producing apparatus. When the water contacts the upper or shorter electrode 26, the relay coil 52 is grounded through the water and the furnace completing the circuit 58 and 30 energizing the coil 52.

Upon energization of coil 52, the armature 54 is raised, breaking the valve circuit 46 at 60 and closing both the valve circuit 48 at 62 and the branch relay circuit 66. The valve device 32 35 is thereby de-energized cutting off the feed of water to the boiler, while valve device 34 is energized opening the delivery of fuel to the burner. The production of heat by the burner converts the boiler water into steam and the water level 40 falls below electrode 26. However, the relay coil 52 is still retained in energized condition due to the fact that its circuit is completed through the branch circuit 66 to the longer electrode 28. Not until the water level drops below the end of the 45 longer electrode will the relay controller be returned to its de-energized condition. At this point the fuel delivery will be cut off while the water feed will be opened and the controller will be ready to commence its cycle of operations 50 all over again. It is to be noted that the automatic control is entirely electrical in character and that it regulates the water level between two extremes providing a normal operating range for the boiler.

55 Conventional house voltage is not satisfactory for establishing a circuit through water, and for that reason a transformer or converter 56 has been employed in the controller for stepping up the voltage through the relay control circuit. 60 This insures the establishment of a circuit through the water when the water is in contact with the electrodes.

In Fig. 2 I have shown a modification of the 65 controller illustrated in Fig. 1. A third electrode is employed in this arrangement and instead of one relay controller, two separate controllers are included. This arrangement is particularly desirable for large steam boilers where 70 it is undesirable to periodically cut off the heating apparatus. Such an arrangement may be adapted, for instance, for locomotive steam boilers. In that case the heating apparatus generally indicated at 16 and including the fuel delivery 18 may be a coal consuming furnace pro-

vided with an automatic stoker for delivery of coal thereto.

The modification in Fig. 1 is provided with a chamber 10 in which are mounted electrodes adapted to be affected by different levels 5 of water in the boiler. An electrically controlled valve device 72, similar to that at 32 in Fig. 1, is employed for controlling the water feed to the boiler. Likewise, a valve device 74, similar to that at 34 in Fig. 1, is utilized for controlling the fuel delivery. Both these valve devices are placed across the main line circuit 10 15 to receive power therefrom as in Fig. 1.

In place of one automatic relay controller as in Fig. 1 two are employed in this modification. 15 The relay switch for controlling the water feed valve 72 is indicated generally at 78. The relay switch for controlling the fuel delivery valve 74 is indicated generally at 80. Both the circuits of these relay switches derive their power from 20 separate secondary windings of the transformer 82.

The relay circuit which includes the switch 78 includes two electrodes 84 and 86 which perform functions similar to the electrodes 25 described in Fig. 1. Instead, however, of establishing circuits through the water to be grounded on the furnace, these two electrodes establish a circuit through the water between themselves and thus, in this manner, close the relay circuit for 30 the switch 78. The circuit of the electrode 86 is provided with a branch 87 leading to a ground connection. This ground circuit 87 is open except when relay switch 78 is in raised position.

A third electrode 88 is included in the relay 35 circuit of the relay 80 and it is adapted to establish a circuit through the water to the furnace to be grounded thereon in order to close the relay circuit for the switch 80. This relay circuit is broken at the spaced contacts 90, but is adapted 40 to be closed upon energization of the relay coil and withdrawal of the core into the coil. A push button switch 92 is capable of momentarily closing the relay circuit across the open terminals at 90 in order to start the sequence of operations. The arrangement of the switch 92 and the open contacts at 90 is used for heating apparatuses which are not capable of automatically 45 firing themselves but must be fired by the operator. For those furnaces or heating devices which are capable of restarting without human assistance, as for instance by a pilot light, the arrangement of the switch devices 90 and 92 may be done away with and the relay circuit extend 50 unbrokenly to the electrode 88.

In the operation of the modification shown in 55 Fig. 2 it is first assumed that the water in the boiler is at a level between the two longer electrodes 86 and 88. Main switch A is then closed. The push button switch 92 is then momentarily 60 closed. Due to the fact that electrode 88 in the circuit of the relay 80 is grounded through the water in the boiler, the coil of the switch 80 will be energized. Energization will close the circuit to the fuel valve device 74 and cause the opening 65 of the valve. Thereafter the heating apparatus will function at all water levels above the end of the longest electrode 88.

The level of the water being between the ends 70 of the two electrodes 86 and 88, the relay switch 78 will remain unenergized due to the fact that relay circuit is open between the electrodes 84 and 86. Accordingly, the switch 78 is in its lower 75 position closing the circuit to the water feed valve 72 causing the opening of the latter and the de-

livery of water to the boiler. The water level thence rises in the boiler contacting the electrode 86. The contact of the water with this electrode has no effect upon the circuit of relay 78 due to the break in the relay circuit still existing between the two electrodes 84 and 86. Upon the water level rising to the shortest electrode 86 the circuit of the relay 78 is closed through the water between the electrodes 84 and 86 and the coil of relay 78 is energized raising the switch armature to upper position and closing the branch circuit 87 to ground.

The raising of the armature switch in relay 78 breaks the valve circuit to valve 72 permitting the latter to close and cutting off the delivery of water to the boiler. The conversion of water into steam lowers the water level out of contact with the electrode 84, but due to the fact that the circuit of relay 78 is grounded both through the electrode 86 and the water in the boiler and through the branch circuit 87 of the relay at the switch 78, the switch is retained in upper position, much in the same manner as in the operation of the device in Fig. 1 until the water falls below the middle electrode 86. Therefore, a normal operating range is permitted the water level in the boiler in which the water level may fluctuate without calling the automatic controllers into operation.

When the water level falls below the middle electrode 86, the ground connection of relay circuit 78 is broken and the switch of the relay 78 falls to close the circuit to the water feed valve control. This operates to cause the feeding of the water to the boiler. But unlike the operation in Fig. 1, the heating apparatus continues to function at this stage. If the conversion of water into steam should exceed the introduction of water into the boiler, the water level will continue to fall until it drops below the longest electrode 88 at which point the ground connection of the relay 80 through the water in the boiler will be broken causing the latter, through the opening of the switch at 80, to de-energize valve device 74 and cut off the supply of fuel. It is seen, therefore, that the heating apparatus continues to function when the water level fluctuates in its normal operating range as well as when the water level falls below this range. It is only when the water level falls extremely low that the functioning of the heating apparatus is prevented.

The relay control 80 and its associated electrode 88 operate as an automatic safety appliance preventing the operation of the heat producing apparatus when there is no or very little water in the boiler. At all other times however the heating apparatus functions, even when water is being introduced into the boiler. Once the relay 80 is de-energized after the water level drops below electrode 88, it is necessary for the operator to momentarily push the button switch 92 to restart the sequence. This provision enables the operator to prepare the heating apparatus for ignition when the fuel is delivered. For those heating devices which are automatically ignited, the switch arrangement 90 and 92 may be dispensed with as previously explained. The arrangement in Fig. 2 is particularly adapted, for those boiler operations where it is undesirable to have the heating apparatus cut off unless absolutely essential.

It is obvious that instead of the electric valve devices 32 and 72 for controlling the introduction of water, some other electrical apparatus may be used as, for example, an electric pump. The

electric pump would take the place of the valve device without disturbing the circuits previously established for the valve devices. Or a steam pump may be used, and the valve devices 32 and 72 may be employed to control the delivery of steam to the pump. The control over the water feed would be the same as that described in connection with Figs. 1 and 2.

In the figures, a boiler 12 is shown. It is clearly within the concept of the invention to apply the control devices to any form of a liquid container. The controller could be associated with a tank in place of the boiler. As an example, a tank could be connected in the return line of a heating system between the radiators or the condensers and the boiler. The tank would receive the condensed products from the radiators and deliver the water to the boiler. The electric controllers would be divided between the tank and the boiler. That is, two of the electrodes 84 and 86 may be positioned in the tank while electrode 88 would be retained in the boiler. The electric control system would function substantially the same as described in connection with the drawings.

Various modifications will be apparent to those skilled in the art, and for that reason I intend to limit myself only within the scope of the appended claims.

What I claim:

1. In an automatic electric controller for controlling the operation of a boiler having a water inlet and an apparatus for producing heat, electric means for controlling the delivery of water through said inlet into the boiler, electric means for controlling said heating apparatus, electric means for controlling said heat and water control means associated with said boiler and provided with contacts adapted to be electrically affected by different water levels in the boiler, all of said electric control means having the circuits opened and closed by a single movable element in accordance with the water levels in the boiler as the same affect the contacts of the electric means associated with the boiler.

2. In an automatic electric controller for controlling the operation of a boiler having a water feed inlet and a fuel consuming apparatus for producing heat, electrically operated means for controlling the feeding of water through said inlet into the boiler, electrically operated means for controlling the delivery of fuel to said heat producing apparatus, a relay control circuit for controlling the operation of said means and including a contact adapted to be electrically affected by the water level in said boiler, a switch under control of said relay for opening and closing the circuits to said control means and adapted when the water level affects said contact in the boiler to render the control means for the water feed operative to cut off the feeding of water, and a retention circuit for said relay also having a contact adapted to be affected by the water in the boiler but at a lower level than said first mentioned contact, said retention circuit adapted to cause the switch to be retained under control of the relay in water feed cut off position until the water level in the boiler falls below the last mentioned contact in the boiler.

3. An automatic electric controller for a steam boiler having a water feed pipe comprising, in combination, an electric operated valve device for said feed pipe adapted upon energization to open and permit the delivery of water to the boiler, a relay including two branch circuits each

having an electric contact adapted to be affected by a different level of the water in the boiler to close and open the relay circuit, said relay controlling a switch in said valve circuit adapted 5 upon the water level rising to the higher contact to open said switch and permit the valve to cut off the water feed and further adapted to maintain said valve in cut off position until the water level has fallen below the lower contact at which 10 time the relay will permit the switch to close whereby the water feed pipe will be opened to fill the boiler.

4. An all electric automatic controller for steam boilers having a water inlet and a fuel 15 consuming apparatus for producing heat which comprises, in combination, electric operating mechanism for controlling the delivery of water through said water inlet into the boiler, electric operating mechanism for controlling the supply 20 of fuel to said fuel consuming device, a plurality of electric contacts adapted to be affected by different levels of water in the boiler to close circuits, and electric means associated with said contacts providing an automatic governor for 25 regulating the operation of said electric operating mechanisms to limit the fuel delivery when the water level is low in the boiler and to limit the delivery of water through said inlet into the boiler when the water level is high in the boiler.

30 5. Automatic electric control apparatus for a boiler having a water feed inlet and a fuel consuming apparatus for producing heat comprising, in combination, electrically operated valve means for controlling the feeding of water 35 through said inlet, electrically operated valve means for controlling the delivery of fuel to said heat producing apparatus, electric control means for controlling the operation of said valve means and including a pair of electrodes adapted to be 40 contacted by different water levels in the boiler, and a switch mechanism having a single movable member operable for controlling the circuits to said water and fuel valve means and adapted in one position to open the water valve means 45 circuit and close the fuel valve means circuit and in another position to open the fuel valve means circuit and close the water valve means circuit.

6. Automatic control mechanism for controlling the heating of a boiler and feeding water thereto 50 comprising, in combination, a boiler, an auxiliary water tank connected to the boiler to maintain a water level variable in accordance with the water in the boiler, a pair of electric contacts extending into said tank and each arranged to be 55 affected at different levels of the water in the tank, a relay circuit associated with said contacts, electrical means for controlling the delivery of fuel for heating the boiler, electrical means for controlling the delivery of water to 60 said boiler, said relay provided with a single movable element operable in one position to close the circuit to the fuel control means and operable in another position to close the circuit to 65 said water control means.

65 7. Automatic control mechanism for a conventional house furnace having a fuel system for delivering fuel for combustion and a boiler provided with a water inlet through which water may be delivered comprising, in combination, electrically 70 operated means for controlling the delivery of fuel, electrically operated means for controlling the delivery of water to said boiler, a unitary relay mechanism adapted to control the circuits of both of said electrically operated means, a 75 single movable element in said relay mechanism

operable in one position to close the circuit to said water control means and in another position to close the circuit to said fuel control means, and a pair of electrodes associated in the relay circuit and extending into contact relationship with the water in the boiler at different levels so as to energize and de-energize the relay as the water level varies within the boiler.

8. Automatic control mechanism for controlling the heating of a boiler and the feeding of water thereto, comprising, in combination, a boiler, an auxiliary tank connected to said boiler to maintain a water level variable in accordance with the water in the boiler, a water feed pipe for delivering water to said boiler, a fuel feed 15 pipe for delivering fuel to a heat producing apparatus, valves in each of said pipes each under control of a separate electromagnetic means, a relay control mechanism for controlling the circuits of said electromagnetic means and including a single movable member operable in one position to open one of said electromagnetic circuits and to close the other and in another position to open the latter circuit and close the former circuit, said relay control mechanism including two electrodes extending downward unequal distances in the auxiliary tank so that the relay control is affected by different water levels in the boiler.

9. Automatic electric control mechanism for controlling the heating of a boiler and the feeding of water thereto which comprises, in combination, a boiler, a heat producing apparatus, a water feed pipe for delivering water to said boiler, a fuel delivery means for delivering fuel to said apparatus, an auxiliary tank connected to said boiler to maintain a water level variable in accordance with the water in the tank, electric means for controlling the feeding of water through said water feed pipe, electric means for controlling the fuel delivery means, an electric control mechanism for controlling said water feed control means and including two electrodes extending downward unequal distances in said auxiliary tank, an electric control mechanism 45 for controlling said fuel delivery means and including an electrode extending downward in said auxiliary tank to a greater depth than said other two electrodes, said first two electrodes adapted to be affected by water levels so as to cause the water feed control to tend to maintain the water level within a range between the ends of said electrodes, and said longest extending electrode adapted to be affected upon the lowering of the water level below its end to cause the cut off of the delivery of fuel to said heat producing apparatus.

10. Automatic electric control mechanism for controlling the heating and feeding of water in a tank which comprises, in combination, a tank, means for feeding water to said tank, means for heating the water, electric mechanism for controlling the feeding of water to said tank, electric mechanism for controlling the operation of said heating means, an electric relay system for controlling said electric mechanisms and including a plurality of electrodes extending into contact relationship with the water in tank, said electrodes adapted to electrically affect the relay system upon contact with the water so as to cause the water delivery and heating means to alter their operation in accordance with the water level in the tank.

11. Automatic electric control mechanism for controlling the heating and feeding of water in a

- boiler which comprises, in combination, a boiler, a conduit to said boiler through which water is conducted, a heating apparatus for heating the water in said boiler, an electric device for controlling said water conduit, an electric device for controlling said heating apparatus, a main circuit including both said electric devices, a relay circuit including a plurality of electrodes adapted to be affected by different levels of water in said boiler and relay switches controlling the circuits to said electric devices, said relay circuit adapted to be rendered operative when the water level in the boiler contacts said electrodes and establishes a circuit through the water in the boiler, and a transformer between said main circuit and said relay circuit operable to step up the voltage for the relay circuit whereby adequate voltage is provided for effective electric transmission through the water in the boiler.
12. Electric control mechanism for boilers comprising, in combination, a boiler having a water feed thereinto, a heating apparatus for converting the water in the boiler to steam, an electric control device for controlling the feed of water to said boiler, an electric control device for controlling said heating apparatus, a plurality of electric terminals associated with said boiler each adapted to be affected by a different level of the water in the boiler, electric means including said terminals in circuit adapted to control said devices to shut off the feed of water when the level of the water in the boiler rises dangerously high and to shut down the operation of the heating apparatus when the water level in the boiler falls dangerously low, said means including a retention circuit adapted when once the feed of water has been shut off to prolong this condition until the water level falls to a predetermined level in the boiler at which time it will function to open the feed of water to the boiler.
13. Electric control mechanism for boilers comprising, in combination, a boiler having a water feed thereinto, a heating apparatus associated with said boiler for converting the water in the boiler to steam, an electric control device for controlling the feed of water to said boiler, an electric control device for controlling said heating apparatus, a plurality of electric terminals associated with said boiler each adapted to be affected by different levels of water in the boiler, electric means including certain of said terminals in circuit adapted to control said water control device to shut off the feed of the water when the water level rises dangerously high in the boiler and to feed water when the water level falls relatively low in the boiler, and second electric means including one of said terminals in circuit adapted to control said heat control device to shut down the operation of said heating apparatus when the water level in the boiler falls to an even lower level than said relatively low level which functions to open the feed of water to the boiler.
14. An electrically controlled heating apparatus comprising, in combination, a chamber containing water, a heating device, said chamber furnishing water for the production of steam by said heating device, a conduit opening into said chamber through which water is adapted to flow and vary the water level in said chamber, electric mechanism controlling the delivery of water through said conduit, electric mechanism controlling the operation of said heating device, electric relay means controlling said heat and water control mechanisms, said relay means electrically connected to a plurality of electrodes extending into said chamber and each arranged to be contacted by a different water level in said chamber and upon such contact to establish a circuit through the water, said electrodes affecting the control exercised by said relay means over said water and heat control mechanisms in accordance with the water level in said chamber.
15. An automatic electric controller for tanks comprising, in combination, a tank adapted to contain liquids, a conduit opening into said tank through which liquid is adapted to flow and vary the level of the liquid in the tank, an electrically operated device controlling the passage of liquid through said conduit, an electric relay mechanism controlling the circuit of said liquid control device, said relay mechanism having a circuit including an electrode arranged in said tank for contact with relatively high levels of the liquid in the tank, said electrode adapted upon contact with the liquid to affect the control exercised by said relay mechanism over the circuit of said liquid control device, a second circuit for said relay mechanism including an electrode arranged in said tank for contact with relatively low levels of liquid in the tank, said second circuit and electrode therefor forming a retention circuit for said relay mechanism adapted to retain the relay mechanism in the condition it assumed when the liquid level rose high enough in the tank to contact said first mentioned electrode until the liquid level falls below the second mentioned electrode.
16. An electrically controlled heating apparatus comprising, in combination, a chamber adapted to contain water, a heating device, a conduit connected to said chamber and through which water is adapted to flow and vary the height of the water level in the chamber, electric mechanism controlling the passage of water through said conduit, electric mechanism controlling the operation of said heating device, an electric relay means adapted to control the circuits of both of said electric control mechanisms, a movable element in said relay means operable in one position to close the circuit of said water control mechanism and in another position to close the circuit of said heating device, and means responsive to the water level in said chamber and electrically connected to said relay means to vary the operation of the latter in accordance with the water level in the chamber.

JOHN E. BRIGGS.
